United States Patent Office

Des. 212,351
Patented Oct. 8, 1968

212,351

COMBINED BOTTLE AND CAP

Carl J. Strobel, Winnetka, Ill., assignor to The Pillsbury Company, Minneapolis, Minn., a corporation of Delaware

Filed Jan. 3, 1968, Ser. No. 10,039

Term of patent 14 years

(Cl. D9—53)

I claim:

The ornamental design for a combined bottle and cap, as shown.
